PISTON EXPANDER

Oscar L. Ulvang, Duluth, Minn.

Application March 23, 1933, Serial No. 662,240

2 Claims. (Cl. 309—12)

This invention relates to piston expanders, and has for its principal object to provide a more efficient and simple device of this character than heretofore known.

5 Another object is to provide a resilient expander having means associated therewith for selective adjustment of its resiliency.

Still other objects and advantages of the invention will appear in the following description 10 thereof.

Referring now to the accompanying drawing, forming part of this application, and wherein like reference characters indicate like parts:

15 Figure 1 is a cross sectional view of the lower end or skirt of a common internal combustion engine piston having three of the expanders applied thereto.

Figure 2 is an elevation of one of the expanders illustrated in Figure 1.

20 Figure 3 is a perspective view of a modified form of resilient expander.

I am aware that resilient expanders for pistons having split skirts are old, but such expanders are not designed for the express purpose of applying expansion to that portion of the piston requiring same, but rather to applying expansive stress more generally to the lower end of the piston, whereas it is well known to those versed in the art that the wear of the piston 25 in a cylinder is upon the opposite sides thereof at right angles to the wrist pin connection therein, thus the necessity of expanding the skirt of the piston in a manner only to compensate for such wear.

30 35 For example the expander known as a bull ring is simply snapped into the skirt of the piston and applies its stress uniformly thereabouts, but only upon a limited annular area about the piston as compared with my preferred form of expander for such purpose. It is to be understood that the instant form of expander is 40 applicable to either a split skirt piston or a solid one, and it may here be stated that to many at least it is quite surprising what effect in the 45 way of diametrical expansion may be had in the skirt of the common piston by application of two of the most simple forms of the invention, as for example illustrated in Figure 3 of the drawing, and these being snapped into place simply 50 with the fingers of the hand.

Referring now particularly to Figure 1 of the drawing, the numeral 1 represents the skirt of a common piston to which is applied one type of the improved expander as at 2, and a different 55 type of the expander as at 3, though, of course,

it is to be understood that different types of expanders in the same piston are not correct in practice, but are here shown simply to illustrate the two different kinds of expanders. The one illustrated at 2 is that type shown in Figure 2 of the drawing in which is installed an adjustable stiffening element in the form of a turnbuckle 4.

5 In providing the type of expander or spring illustrated at 2, it is preferred that the general 10 shape be as illustrated, having an arcuately shaped or bowed central portion with the ends arched in reverse relation and centrally of the middle portion is an oval or elliptically formed opening 5 in which is installed the turnbuckle 4, 15 the opposite pintles 6 of which are provided with right and left hand threads so that the turning of the adjusting element of the turnbuckle will either extend or retract the pintles 20 uniformly.

The advantage of such an adjustable spindle 25 will be appreciated when it is considered that extreme nicety of expansion from time to time is essential for proper relationship of the piston to the cylinder as wear takes place. Such adjustment may be accomplished from time to time without the renewal or careful selection of an 30 expander for a specific requirement.

It is readily appreciated that if an expander 35 having no adjustability is selected which is a trifile too stiff, it will cause decided and necessarily damaging wear until finally automatic adjustment takes place, and then will last only for a given time. However, where this more careful adjustment is not necessary or deemed 40 advisable, the simpler form of expander as illustrated at 3, or the one shown in Figure 3 of the drawing at 7 may be employed, and in which instance the effect of the expander only utilized to the limit of its inherent properties. The 45 illustrations at 3 and 7 in Figure 1 may represent an expander such as shown in Fig. 3 or one as shown at 2, without the auxiliary stiffening device as previously described, or with it as preferred.

An advantage resides in such an expander as shown at 2 without the stiffener in that it is much wider than the expander shown at 7 and provided with spaced contact terminals 8 at 50 either end thereof, though, of course, necessitating two holes or depressions within the inner wall of the skirt for registration therewith. This materially spreads the effect of the expander longitudinally of the skirt, substantially 55

differing from the effect of a bull ring expander as previously mentioned.

For an abnormally wide expander the central portion may be cutaway as indicated in dotted lines at 9 upon either one side or both as required, depending upon the position of the expander in the piston.

Having thus described my invention, what I claim and desire to secure by Letters Patent, is:

- 10 1. A skirt expander for pistons comprising a flat wide spring having an arcuately shaped central portion with a central opening there-

through, and an adjustable expansile element within said opening.

2. A skirt expander for pistons comprising a flat wide spring having an arcuately shaped central portion and reversely curved ends, means at the ends of the spring for fixed engagement with the walls of the piston, said spring also having a central opening therein elongated longitudinally thereof, and a rigid adjustable expansile element within said opening.
